UNITED STATES PATENT OFFICE.

SHANKER ABAJI BHISEY, OF NEW YORK, N. Y.

MACHINE FOR CASTING AND ASSEMBLING TYPES, LEADS, RULES, &c.

1,364,235.

Specification of Letters Patent.

Patented Jan. 4, 1921.

Application filed April 24, 1917. Serial No. 164,199.

To all whom it may concern:

Be it known that I, SHANKER ABAJI BHISEY, a subject of the King of Great Britain, temporarily residing at New York, N. Y., have invented new and useful Improvements 5 in Machines for Casting and Assembling Types, Leads, Rules, &c., of which the following is a specification.

One object of my invention is to provide a 10 mold for use in a type-casting machine which will be adjustable universally for small or large type quads, leads and rules without requiring interchangeable parts, and which will produce accurate types. 15 Other objects are to provide means for automatically assembling the types, etc., in a row of predetermined length, to cast leads and rules of required length and automatically transfer such assembled types, leads or rules 20 into a galley.

The important features of my invention are as follows:—The mold is formed with 25 top and bottom T shaped blocks; the mold is easily and accurately adjustable to any body size of the type without requiring any interchangeable parts and when adjusted the top and bottom parts determine the body size of the type and remain absolutely permanent to produce the body of the type with the same 30 accuracy all the time. The parts of the mold blocks beyond the mold portion form a channel identical in width with that of the mold and remain stationary so that the cast types, etc., are ejected from the mold into this packing 35 channel in a straight line; the mold is easily convertible to cast spaces, leads and rules; leads and rules are first cut or cast in short lengths in the mold and any surplus trimmed off while assembling those into the galley. Large quads and quad blocks or 40 printers' furniture are cast hollow and in long lengths. Means are provided for automatically assembling types, etc., in rows of required length and transferring those to a 45 galley. There is a nipple plate with a nozzle which shifts away from the mold after casting and during casting the choker is withdrawn from the passage of the molten metal to allow free flow of metal into the 50 mold.

The construction of the mold and its associated parts and assembling and galley mechanism is illustrated in the accompanying drawings in which Figure 1 is the front 55 view of the mold with the matrix holder removed and the base portion shown broken

off. Fig. 2 is a vertical section line 2—2 in Fig. 1. Fig. 3 is a rear elevation of the mold. Fig. 4 is a plan of the mold with the top half removed. Fig. 5 is a section on line 60 5—5 in Fig. 1. Figs. 6 and 7 are broken details of portions of the mold side walls. Fig. 8 is a broken view of the mold with alternative method of adjusting its parts. Fig. 9 is a sectional view of the bottom part of 65 the mold as adapted to cast spaces, leads and rules with means to cut or cast short leads and rules taken on line 9—9 of Fig. 13. Fig. 10 is a plan view of same parts showing method of severing leads and rules and 70 ejecting types and leads and rules by a fork shaped pusher. Fig. 11 is a section on line 11—11 in Fig. 10. Fig. 12 shows a continuous strip of lead or rule cast with interlocking parts. Fig. 13 is a broken plan view of 75 one form of cutting mechanism. Figs. 14 and 15 are details of a modified form of means for operating the severing mechanism. Fig. 16 is a side view of the assembling and galley mechanism. Fig. 17 is a 80 front view of same. Fig. 18 is a plan view showing drum. Fig. 19 is a broken plan of the galley and pusher plate. Fig. 20 is a plan showing portion of packing and assembling channels when partly shifted. Fig. 21 85 is a plan view showing method of casting hollow quads and Fig. 22 shows details of parts.

The table or base of the machine is designated by numeral 1. The mold is composed 90 of a bottom frame 2 and top frame 3. The parts forming the mold are made of two T shaped blocks. Upper block 4 is vertically slidable in frame 3 and lower block 5 is horizontally slidable in frame 2. Block 4 is composed of a member 6 of the same width as a type without its face and a side plate 7 having its upper end inclined, is fixed to member 6 by a screw. See Fig. 2.

Mold block 4 has a slot in which a side 100 wall member 9 is located. The block 4 is moved vertically by screw 10 having a collar 11 seated in the frame (Fig. 2). The member 6 is cut away at its edges and made to slide in the frame as shown in Fig. 5. On the other side of the member 6 are side plates, 12 fixed to the upper frame and 2^a fixed to lower frame and recessed in the center. A member 13 is slidably located in a groove in wall 12. Its lower edge is inclined 110 at 14 and forms the top of the tang or jet mold and covers the top of the tang or jet

forming member 15 which is inclined toward the mold and opens the passage of molten metal into the mold according to its thickness as shown in Fig. 4. Member 13 is adjusted by screw 16 having a collar 17, journaled in the frame Figs. 2 and 3. The side wall member 9 is kept pressed toward the mold by spring plungers 18 and its lower edge is grooved at 19 to fit over the rib 20 on the lower part 21 of the packing channel.

Frame 3 supports at the front a sliding incline plate 22 dovetailed at 23 (see Fig. 2) which is adjusted by a screw 24 having a lock nut 26 and operating head 27. A rack 28 is slidably fitted on the front of the incline 22 and its rear part 29 is dovetailed in the incline. The rack is slightly adjustable to cast type in fractions of a point by interposing a suitable packing piece 30 between its bent part 31 and bracket 32 by means of a screw 33.

An indicator plate 34 is fixed to the frame to show the body size adjusted by means of the edge 36 of the incline 22 traveling under the scale. When adjusted the incline is fixed in position by a projection 37 connected to screw 38 mounted in bracket 39 (Fig. 22).

Frame 3 with the top block turns on a hinge 41 and is fixed in position in lug 42 by a bolt 25. Side wall member 9 is lifted up by spring 9^a to bring its lower edge flush with the bottom of the block 4 and is pressed downward to form the side of the mold by the operation of the rock lever 40. Member 6 has a lateral extension 6^a which forms the top of the packing channel. A catch 49 is provided to retain the packed type.

The lower mold block 5 consists of a middle member 5^a held between two side plates 5^b and 12^a. A removable member 21 forms the bottom of the packing channel and is provided with a pin cutter 50 for cutting additional nicks in the type, a groover 51 to cut a nick in the foot of the type and a projection 52 to form one side of a matrix vise.

A side wall member 46 with an adjusting screw 46^a is slidably located in the member 5^a and forms one side of the mold. Packer 48 is slidably mounted on the frame 2 and reciprocates by the operation of the lever 54. This packer has an extension 48^a slightly thinner than the thinnest type body and a plate 48^b is provided for large type bodies. Also a pin or lug 48^c which pushes the tang member 15 by engaging the edge of the same (Fig. 4) against the tension of spring 15^a. The extension 48^a may be replaced by a packing arm 48^d (Fig. 4).

The movement of the packer plate 48 may be shortened when casting leads and rules without changing the stroke of the rock lever 54, by simply removing the abutment piece 48^e in the end of the block, which is

shown removably held in place by screw 48^f. This same screw also serves to removably secure the plate 48^b in position.

Fig. 8 illustrates an alternative method of adjusting the mold to the required body size. Instead of two inclined plates a micrometer adjusting screw 66 is here provided held in a bracket 66^b fixed to the frame and provided with a vernier plate 66^a coöperating with the markings on the screw to read the fractions of a point. For instance if each turn of the screw indicates 4 points, on the vernier plate the four points and their subdivisions are marked in radial lines to enable adjustment of the screw to any point or its fraction. After adjusting the micrometer screw, the mold block is drawn up by the nut 67^a held in the frame and engaging screw 67 until the end abuts against the micro-screw end.

Provision is made for shortening the mold space, for the casting of spaces, quads and the like by employing a plate 56, projecting into the front end of the mold space as indicated in Figs. 7, 10 and 13. This plate may be fixed to the member 21, or, if it is provided with a notch 56^a to cast a projection on the face of the spaces, quads, leads or rules, for engagement by the plate 48^d of the packer, then it is suitably secured to and reciprocated by the matrix holder 57. This plate is reversible as shown in Fig. 13 when not casting the projection. The holder may be of any well known construction and be reciprocated as by means of a lever 57^b. The member 9 is provided with an adjustable piece 9^b to engage on the plate 56 (Fig. 6.)

A cylindrical nozzle 89 reciprocates in the frame 88 of the metal pot and has a metal passage 88^a connected with the metal well. A choker 90 reciprocates in the nozzle, and its end is made spherical and fits tightly around the port made in the concave surface of the nipple plate 86. The other end of the choker is spring pressed and is so held close to the mouth of the nozzle when free. The nipple plate 86 is loosely held on two bolts 86^a fixed to the frame wall 2^a and is pressed away from the mold by springs 86^b coiled around the bolts.

In operation the nipple, nozzle and choker are pressed against the mold by lever 89^a. Just before the piston forces the metal the choker is withdrawn by the lever 90^a sufficiently to clear from the mouth of the inclined passage 88^a so that the metal is forced straight into the mold without any obstruction.

Immediately after casting, the choker is allowed to resume its normal place to close the port in the nozzle so as to cut off the metal and prevent any metal remaining in the nozzle end. Then the nozzle is retracted, releasing the nipple plate and allowing it

to separate from the mold surface thus preventing its surface and the nozzle end from cooling off. This is an important feature of my nozzle and nipple construction over 5 those hitherto employed as is also the feature of retracting the choker from the metal passage.

For casting large types, the jet and the nozzle are preferably arranged to come in 10 the center of such types by adjusting the walls 13 and 12^a to bring the jet in the central position and also by adjusting the frame 88 on the side of the metal pot to bring the nozzle and nipple ports in the 15 center of the jet by any suitable means.

In the operation of the mold, the incline 22 or the micrometer screw 66 as the case may be, is adjusted in the frame 3 to cast 20 a type of any required body and locked in position and the mold block 4 drawn against it and fixed. Then the side wall 46 of the lower mold block is adjusted so that its upper end abuts against the lower surface of the top mold block 4. The side wall 9 25 is forced down into abutting engagement with the upper surface of the packing channel. This completes the four sides of the mold. The front side is closed by the face of the matrix 57^a which is fixed in a holder 30 57, reciprocated on rails 57^c. The rear of the mold is made up by member 13 and tang bar 15 which latter is interchangeable with similar bars varying in thickness to provide for a narrower or wider opening for the 35 metal according to the size of the type. The front edge of the tang bar being inclined and always keeping in alignment with the inside surface of the side wall 46 as it is pulled by spring 15^a against a projection 46^b fixed to the side of the member 40 46, the length of the opening always corresponds with the set width of the type. The set width of the mold is adjusted by holding the matrix 57^a in the vise formed 45 between a projection 53 fixed to the frame 2 and the lug 52 fixed to the member 21 and adjusting the mold block 5 to it by turning the screw 47. When a linotype matrix is used a plate 53^a may be provided to 50 make up for the side wall usually allowed on electrotype-matrices.

After casting by operating the pump in the usual way, the side wall 9 returns to its normal position thereby opening the way for 55 the type to pass into the packing channel. I prefer to retain the side wall 46 in its casting position, without lowering it in which case the type is ejected by the packer 48 pushing tang bar 15 and thereby the tang 60 of the type on one side and on the other side the end of the adjustable packer bar 48^a abutting against the face of the type and the movement is so arranged that the type is ejected evenly by pushing simultaneously at 65 the tang and face of the type. In case of

space type, the plate 56 as above mentioned, has a recess 56^a (Fig. 10) to cast a projection extending beyond the edge of the side wall 46. However the side wall 46 may be made to retract by connecting its adjusting 70 screw 46^a to the plunger 55, in which case the type is pushed by the tang bar 15 and the full face of the packer end 48^a. After ejecting the type into the channel the packer recedes to its normal position, the side wall 9 75 is lowered, the matrix closes the front and the mold is ready for another casting.

While the types are being packed in the channel a plunger 44 (Fig. 3) is operated by a lug 40^a fixed to the lever 40 to cut the 80 jet piece of the type which falls into the chute 45, the nick is cut at the foot and also in the body by the respective cutters and the types come out of the channel completely finished and ready for use. The 85 shavings also pass in chute 45.

In an alternative method the frame 3 with the mold block 4 is allowed to turn on hinge 41, the bolt 25 having been removed and is sufficiently lifted by a lever 43 90 pivoted to the frame end 43^a to allow cast type to pass under the side wall member 9 and consequently there is in this case no need for reciprocating member 9. A suitable plate may be provided in this construction to form the top of the packing channel. 95

As the reciprocation of the side wall member 9 is unnecessary when operating in the manner just described, this member may be suitably latched in its downward position, as by means of the screw or pin indicated at 9^c. The end of the lever 40^b is pivoted at 40^c to turn away when not operating the member 9 and locked in position by a bolt 40^d. 100

Leads and rules are required to be cast in a continuous long strip and cut in lengths as required. For casting those the member 9 is constructed as shown in Fig. 7 as having an adjustable tang forming member 13^a 110 to form a continuation of the tang mold and the lower end of this member is without a groove for the nick and without the adjustable plate member 9^b. Member 21 is also replaced by another member 21^a (Figs. 10 and 13) having no rib 20 for the nick or cutter 50 but provided with a cutter 58 (Fig. 9) or a mold blade 58^a (Fig. 11). The member 9 remains stationary with its lower edge flush with the bottom of the top block 4 and 120 the member 13^a is adjusted in alignment with member 13 to allow a continuous strip of lead or rule to be cast and travel through the channel and be packed by the packer. In order to allow the metal to unite firmly 125 with the portion previously cast, a member 46^b is fixed to member 46 by a screw 46^c to bring its edge level with the wall of 46, and passes through the member 21^a into the mold so as to form a V shaped space in the 130

130

end of the piece cast, which being filled up by the metal of the next casting, forms a firm and solid joint therewith (Fig. 12). For casting leads the plate 56 or 56^a is used 5 the same as for space type but no such plates are needed for casting rules which are of the same height as the type. The projection cast by 56^a is trimmed off by cutter 21^b.

Leads and rules are required to be cut into 10 predetermined lengths and this is accomplished either by employing a cutter 58 (Fig. 9) or a blade 58^a (Fig. 11) to sever the casting in the mold. While a casting operation occurs at one point, the end of 15 the cutter 58 at a point in advance, severs the strip and enters a slot 58^b where the cut portion is deposited and slides away owing to the inclined bottom of the slot 58^b. The blade 58^a is designed to enter the mold space 20 and severs the casting by dividing the flow of the metal.

These severing blades are shown as operated in the present illustration by a series 25 of cams 60 acting on the lower ends 58^c of the severing blades. In Figs. 1 and 2 these cams are shown slidably engaged in undercut grooves 61 in the face of a wheel 62 which is provided with ratchet teeth 63 engaged by an operating pawl 64. This 30 pawl is reciprocated once to each casting operation. If the strip is to be severed at each casting operation, the cams are all disposed in their slots so as to engage and operate the severing blade, but if the strip is to 35 be cast in certain length as is customary, certain of the cams are shifted in their slots out of the plane of engagement with the severing blade, so as to cause operation of said severing blade only at certain predetermined intervals. Another method of 40 accomplishing this intermittent operation is illustrated in Figs. 14 and 15, wherein the cams 60^a are shown detachably or adjustably engaged in similar undercut seats 61^a, 45 in an endless chain 62^a mounted on a spur wheel instead of a grooved wheel 62.

For casting thick quads in long lengths commercially known as printers' furniture, the matrix or plate 56 is provided with a 50 core or projection 56^b. I preferably sever such quads like leads and rules by dividing the metal in the mold by means of the mold blade 58^a which is preferably located at one side of the mold as shown in Fig. 21 to be 55 free from the plane of the core 56^b. The quad block end is trimmed of the surplus by the plate 78 in the same way as lead or rules.

Collecting and packing into galley.—
60 Types, leads or rules as they come out of the package channel are collected in one of the channels 68 of an octagonal drum arranged close to the packing channel and freely revolving on a shaft 68^e, Fig. 16. 65 The channels are formed between slidably

walls 68^a and fixed walls 68^b. An escape-
ment wheel 69 is fixed to the outer side of
the drum and has the same number of teeth
as the channels. A pawl lever 70 has its
one end pivoted to the shaft 68^e and the 70
other end provided with a turning head 70^a
through which a round headed screw 70^b
passes. The pawl 70 has a tooth 70^c and a
pivoted catch 70^d opposite to it, said parts
being so arranged that when the tooth 70^c 75
is withdrawn, the escapement wheel 69 is
free to move one tooth and is stopped by the
other catch 70^d coming in front of the sec-
ond tooth, similar to the action of the well
known escapement movement on typewriter 80
carriages.

A plate 71 is fixed to the outer face of the
drum and has inclined parts 71^b. A circu-
lar plate 71^a is fixed to the inner face of the
drum touching the center of the channels. 85
To the sliding wall 68^a a plate 68^e having a
rib to fit the nicks of the types is removably
fixed by dovetailing. To the lower ends of
the walls 68^a pins 68^d are attached working
in slots 71^c in the plates 71 and 71^a. The 90
wall 68^a is pulled back from both ends by
levers 72 each operated by a link 72^a con-
tacting with the cam 73 and brought to nor-
mal position by springs 73^a at each end. A
guide plate 74 is fixed to the adjustable wall 95
77^b of the galley 77. Another guide plate
75 is fixed to the other end wall 77^a of the
galley. A cover plate 76 is at one end fixed
to the wall 77^a and its other end passes over
wall 77^b which is adjustable to vary the 100
width of the galley. A sliding piece 77^c
is provided in the end of the wall, 77^b to
project into the groove 78^c of the packer
plate 78 to prevent types from falling out.
Packer plate 78 has its one end provided 105
with a steel plate 78^d to form a cutting edge
and an arm 78^a is fixed to its back. A bolt
78^e fixed to plate 78 forms an adjustable jaw
and the other jaw is formed by end of the
arm 78^a. The plate 78 is reciprocated by 110
lever 80 more or less according to the size
of the type packed by adjusting the jaw.
The lever 80 is fulcrumed to a bracket 80^b
and has a roller 80^a. It is operated by cam
79 fixed on the shaft 84. The plate 78 is 115
pulled to normal place by spring 78^b. A
spring controlled pusher 81 is pressed by
lever 81^a to push the row of type leads or
rules well into the channel. The lever 81 is
pressed by a spring 81^b and operated by 120
cam 82 fixed to the shaft 84. The shaft is
rotated by gear 83 which is connected to the
main shaft by suitable gearing or chain 83^a
in such a way that it makes one turn pref-
erably to several turns of the main shaft. 125
An angle plate 85 adjustable to the required
width of the galley remains at the back
and moves with the row of type leads or
rules. The rear end of the galley is sup-
plied with a duplex chamber 77^d and 77^e 130

with walls 77^a and 77^b and plate 85 so that when one chamber is filled the empty one is brought in alinement with galley 77 and the contents of the filled chamber removed.

- 5 *Operation.*—Bolt head 70^b is adjusted to project into the channel 68 to collect the row of types or hold leads or rules of required length. When the channel is full the bolt is pushed back by the row which in turn 10 swings back the pawl 70 and releases the drum to shift the drum one step, that is to shift the full channel away and bring an empty channel in its place. The bolt head may sink a little deeper into a groove made 15 in the channels. The drum in its rotation lifts up the bolt by the sleeve 70^a turning on the incline 71^b and then the bolt drops into the next empty channel and resumes its normal position ready for a fresh line. 20 The walls 68^a and 68^b are made little short toward the packing channel end as seen in Fig. 20 and the end of the rib 20 of packing platform 21 (Fig. 1) projects onto the side plate 71^a. The end of the guide plate 75 25 being close to the wall 68^a any type beyond it are held back in the packing channels ready for entering into the next empty channel (Fig. 20). In packing leads and rules this guide plate 75 is dispensed with. 30 The width of the galley is adjusted to the required length which also adjusts the guide plate 74. The end of the wall 77^a is fixed to bring its edge at a distance from the fixed partition 76^a to correspond with the thickness of the type, etc., and it also adjusts the 35 cover plate 76. The row of types, etc., in the first step assumes an inclined position, (Fig. 16) and in the second step a vertical position in alinement with the channel formed between wall 76^a and cover 76. 40 When the wall 68^a is moved the row of type falls straight in the galley. The pusher 81 pushes the row inward and the packer 78 packs it into the galley. In the case of leads and rules the portion 68^c is removed. 45 The lead and rules may be cast of the exact length by accurately adjusting the width of the mold but are preferably cast a little longer in the first place, dropped into the 50 galley and when pushed inward by packer 81, and packed by packer 78, their surplus ends are cut off between the edges 78^a and the wall 77^a as seen in Fig. 19 and then packed into the galley. The bolt 78^c being 55 adjusted to give sufficient throw the row of types, etc., when packed comes flush with the edges of the walls 77^a and 77^b.

60 The operation of various members and parts of the machine described above are controlled by suitable levers coöoperating with their respective cams mounted on the main shaft of the machine which being of usual construction and readily understood by those skilled in the art are not described 65 and illustrated.

The best construction of the parts of the machine are shown as illustrated in the drawings and described in the above specification and may be modified in several ways without departing from the spirit of my 70 invention. For instance the adjustable incline 22 with its elements instead of being associated with the top frame 3 as shown in Figs. 1 and 2 may be associated with the wall 7 of the block 4 and the top frame 3 75 provided with a fixed inclined surface to co-operate with the adjustable incline to serve some purpose. Similarly instead of the adjustable incline being only on one side of the member 6 it may be provided on both the 80 sides and such inclines may be connected at the base and operated by the common screw 27.

Having now described the invention what I believe to be new and desire to secure by Letters Patent is:—

1. A mold for casting type comprising upper and lower T shaped blocks relatively adjustable to form between them a mold space, each block containing a sliding member which forms one side of the mold during the casting operation and means for withdrawing both the sliding members into the blocks after casting to allow the ejecting of the cast type from the mold into a packing 95 channel.

2. In a combination like that of claim 1, a packing channel and means for ejecting the cast type into the packing channel.

3. A combination like that of claim 2, 100 wherein the ejecting means consists of a jet bar coöperating with the side wall forming member of the lower T shaped block and sliding longitudinally to eject the type from the mold into the packing channel.

4. A mold for casting type comprising upper and lower T shaped blocks relatively adjustable to form between them a mold space, the upper member having a movable side wall forming member, means for withdrawing the same after casting, a packing channel adjacent the mold, a jet bar operating on the jet end of the type and a packer bar operating on the face end of the type to transfer the type from the mold into the 115 packing channel.

5. A mold for casting leads, rules and quads comprising upper and lower T shaped blocks relatively adjustable to the desired thickness of the leads, rules or 120 quads, the upper block having a side wall forming member remaining in the raised position to allow the section of leads, rules or quads cast in the mold to pass underneath it, the lower block having a slid able member forming a side wall of the mold, means for shortening the width of the mold consisting of a plate of required thickness interposed between the upper and lower mold block surfaces, means for forming a con- 125 130

tinuation of a jet mold and means independent of the mold for pushing the section of the lead or rule to a distance corresponding to the length of the section cast.

5 6. A mold for casting leads, rules or quad blocks comprising upper and lower **T** shaped blocks relatively adjustable to the desired thickness of the lead or rule, and a plate coöperating with the wall of the lower block to leave a hollow undercut space in the end of the section of the lead or rule when the cast is made.

10 7. A mold for casting lead, rule or quad blocks comprising upper and lower blocks relatively adjustable to the desired thickness of the lead, rule or quad blocks, and means for cutting the strips of lead, rule or quad blocks in predetermined lengths wherein the cutting means consists of a blade sliding into the mold space to cut or separate the section of the lead or rule by dividing the flow of metal during casting operation.

15 8. A mold for casting spaces and quads comprising upper and lower **T** shaped blocks relatively adjustable to form between them a mold space to cast the required size of type, means for shortening the width of the mold comprising a plate interposed in the end of the mold space and provided with a notch to cast a projection on the end of the space or quad, and an adjustable member coöperating with the side wall of the upper mold block to abut on the top of the interposed plate.

20 9. A mold for casting type comprising upper and lower **T** shaped blocks relatively adjustable to form a mold space between them, the side wall member in the upper block being held stationary and the upper block, being hinged and after casting being adapted to turn on the hinge and rise sufficiently to allow the cast type to be ejected from the mold into a packing channel.

25 10. A mold for casting quad blocks comprising upper and lower **T** shaped blocks relatively adjustable to form a mold space the required size of quad or quad blocks, means for shortening the width of the mold, a projection or core to cast hollow in the body of the quad or quad block, means for cutting quad block in predetermined lengths, means for assembling and packing the same in a galley, and means for trimming surplus from the end.

30 11. In a type casting machine, mold blocks having opposed faces providing opposite walls of a mold chamber, means for relatively adjusting said blocks toward and away from each other to vary the width of said mold chamber in one direction, an extensible side wall member mounted in one mold block and extensible at an angle to the mold face thereof into engagement with the mold face of the opposite block, an extensible side wall member mounted in said oppo-

site mold block and extensible at an angle to the mold face thereof into engagement with the mold face of the first mold block, means for relatively adjusting the mold blocks laterally in respect to each other to approach 70 and separate said side wall members to thereby vary the width of the mold chamber in the other direction and means for automatically retracting said mold wall members into the mold blocks to thereby open 75 the sides of the mold chamber.

12. A mold for casting type and the like comprising upper and lower fixedly supported but relatively adjustable blocks having opposed faces forming between them a channel, retractable members projecting each from one of the blocks into engagement with the other block and spaced to divide a section of the channel into a mold chamber, means for closing the back and front of said 80 mold chamber, means for charging the mold chamber, means for retracting the removable end wall members to open the mold channel and an ejector operating in the mold channel after the retraction of said members 90 to shift the molded product beyond the mold chamber section of the channel.

13. A mold for casting type and the like comprising relatively fixed upper and lower blocks spaced one above the other to provide 95 a channel therebetween, spaced end wall members carried each by one of said blocks and projecting into the channel to separate a portion of the same into a mold chamber, means for retracting said members clear of the mold channel and an ejector working in the cleared mold channel.

100 14. A mold for casting type and the like comprising relatively fixed upper and lower blocks spaced one above the other to provide 105 a channel therebetween, retractable elements projecting from one of said blocks across said channel to separate a portion of said channel into a mold chamber, means for retracting said elements clear of the channel 110 to thereby open the mold chamber to the rest of the channel, means for relatively adjusting the upper and lower blocks comprising a laterally shiftable wedge engaging one of the blocks, a rack mounted on said wedge, 115 a screw engaging said rack and means for securing the rack in different adjusted relations on the wedge.

120 15. A mold for casting lead, rule or quad comprising spaced mold blocks having opposed substantially parallel mold walls, a retractable member extending between said mold walls and forming a side wall for the mold chamber, said side wall member having an undercut projection on the mold wall face 125 thereof for forming an undercut groove in the face of the product cast in the mold chamber, means for retracting said member and means for advancing the cast product while said member is retracted to thereby 130

place the undercut grooved portion thereof in position to be engaged by the metal of the succeeding casting.

16. A mold for casting lead, rule or quad
5 comprising spaced mold blocks having op-
posed substantially parallel mold walls, a
retractable member extending between said
mold walls and forming a side wall for the
mold chamber, said side wall member hav-
10 ing means on the mold wall face thereof for
producing a dovetail element on the product
cast in the mold chamber, means for retract-
ing said member and means for advancing
the cast product to bring the dovetail ele-
15 ment thereof into position to be engaged and
interlocked with a subsequently cast product.

17. A mold for casting type comprising
upper and lower substantially **T** shaped
blocks having movable side wall forming
20 members and relatively adjustable to form
between them a mold space, means for re-
tracting the movable side wall forming

members after casting, a jet bar operating on
the jet end of the cast product, a packer bar
operating on the face end of the cast product 25
and an ejector operating on the intermediate
portion of the cast product.

18. A mold for casting type comprising
upper and lower substantially **T** shaped
blocks having movable side wall forming 30
members and relatively adjustable to form
between them a mold space, means for re-
tracting the movable side wall forming
members after casting, a packer bar operat-
ing on the face end of the cast product and 35
an ejector operating on the body of the cast
product.

In testimony whereof I have hereto set
my hand in presence of two subscribing wit-
nesses.

SHANKER ABAJI BHISEY.
